UNITED STATES PATENT OFFICE.

JOHN EDWARD POINTON, OF PETERBOROUGH, ENGLAND.

MACHINE FOR PREPARING RUBBER.

1,138,410

Specification of Letters Patent.

Patented May 4, 1915.

Application filed January 21, 1914. Serial No. 813,501.

To all whom it may concern:

Be it known that I, JOHN EDWARD POINTON, subject of the King of Great Britain, residing at Westwood Works, Peterborough, 5 in the county of North Hants, England, engineer, have invented certain new and useful Improvements Relating to Machines for Preparing Rubber, of which the following is a specification.

This invention relates to machines for the preparation of rubber for industrial purposes of the type in which a batch of washed crude rubber is subjected to the action of rotating blades or their equivalent arranged 15 in intercommunicating chambers, and has for its object to provide for the more ready and effective drying or mastication of the said rubber and incorporation therewith of the usual ingredients required to adapt it 20 to meet various services.

The invention comprises the improved arrangement and combination hereinafter described and claimed of the rotating elements and the intercommunicating chambers 25 wherein they operate.

Referring to the accompanying sheet of explanatory drawings, Figure 1 is a sectional plan and Fig. 2 a sectional end elevation representing, in diagrammatic form, the 30 application of the invention in one convenient manner to a combined drying or masticating and incorporating machine, provided with a pair of intercommunicating chambers each having a rotatable operating element mounted therein.

The same reference letters in the two views indicate the same or similar parts.

The said rotatable operating elements each consist of a central boss like or barrel portion as *a* having a single spiral blade *b* 40 extending along it. At one end of each element the spiral blade terminates at the extremity of the boss, but at the other end (which may be termed the leaving end) it falls sufficiently short of the adjacent extremity of the boss to provide a relief or clearance as *c* for the passage of the material therethrough. The amount of such clearance is made to suit the degree of pressure that is to be imposed upon the material 45 as it is traversed through the chambers by the action of the blades. As will be seen from the drawings, the clearance spaces *c* are at the opposite ends of the respective 50 elements.

The complete blades, propellers, or rotat-

ing elements, may be driven in any convenient manner, at equal or varying speeds.

After its traverse through one chamber, under the operation of the rotating element therein, and its passage therefrom to the adjoining chamber, the material, or the main portion of the same, is in like manner traversed, in the reverse direction, to the leaving end of that chamber and from thence is returned to the first named chamber, thus completing the cycle of movement. This cycle is continuously repeated until the drying or mastication of the material and the incorporation therewith of the desired ingredients has been completely effected. During the rotation of the blades or operating elements some part of the material under treatment will be forced back through the aforesaid relief or clearance apertures or 75 by-passes *c*. The provision of such by-passes is found to greatly facilitate the process of preparing the material for service.

The arrows *d* indicate the directions of rotation of the respective elements, while the arrows *e* indicate the main directions of traverse of the material through the respective intercommunicating chambers *f* and *g*. Between the said chambers there is a partitioning ridge as shown extending from end 85 to end of the chamber.

Instead of the axes of the blades being arranged in a horizontal plane the axes may be slightly superimposed or the one higher than the other. The blades may be varied in shape and a by-pass such as *c* may be made at each end of each blade.

Having thus described my invention what I claim as new and desire to secure by Letters Patent is:-

1. In a rubber preparing machine, the combination of a member comprising intercommunicating chambers, a continuous partition or ridge between said chambers, and propellers in said chambers and bypasses at 100 the ends of the propellers as set forth.

2. In a rubber preparing machine the combination with a member comprising intercommunicating chambers a continuous partition or ridge between the said chambers, a propeller in each chamber, and a bypass at one end only of each propeller, the bypasses in the respective chambers being located at opposite ends.

3. In a rubber preparing machine, the combination of a member comprising intercommunicating chambers, a continuous par-

tition or ridge between said chambers, a propeller in each chamber having a continuous spiral blade, one end of which extends to the end of said chamber, the opposite end of 5 said blade spaced away from its adjacent end of the chamber, to form a by-pass, the by-passes in the respective chambers being located at opposite ends.

4. In rubber preparing machines, the 10 combination consisting of intercommunicating chambers, a partitioning ridge between the said chambers and extending from end to end of the same, propellers in the said chambers, and by-passes at the ends of the 15 propellers, as set forth.

5. In rubber preparing machines, the combination consisting of intercommunicating chambers, a partitioning ridge between the said chambers and extending from end to 20 end of the same, a propeller in each chamber, and a by-pass at one end of each propeller, the said by-passes being at opposite ends of the chambers, as set forth.

6. In rubber preparing machines, the combination consisting of intercommunicating chambers, a partitioning ridge between the said chambers and extending from end to end of the same, a propeller in each chamber having a continuous spiral blade one end of 25 which coincides with the corresponding end of its chamber while the opposite end falls sufficiently short of the corresponding end of the chamber to provide a by-pass, the said

by-pass in the one chamber being at the opposite end to the like by-pass in the adjoining chamber, as set forth. 35

7. In a rubber preparing machine, the combination of a trough comprising intercommunicating chambers, a partition or ridge extending longitudinally from end to 40 end of the trough to form said chambers, a continuous spiral propeller in each chamber occupying approximately the entire width, one end of said propeller extended to the end of its chamber, the opposite end spaced away 45 from its adjacent end of the chamber to form a by-pass, the by-passes in the respective chambers being located at opposite ends.

8. In a rubber preparing machine, the combination with a trough provided with intercommunicating chambers having curved walls, a partition or ridge extending entirely from end to end of the trough dividing the same into said chambers and having 50 oppositely curved faces, a continuous spiral propeller in each chamber, filling the same laterally and having by-passes at one end of each propeller.

In testimony whereof I have signed my 60 name to this specification in the presence of two subscribing witnesses.

JOHN EDWARD POINTON.
